(57) **CLAIM**

The ornamental design for a coconut drilling device, as shown and described.

DESCRIPTION

FIG. 1 is a front elevational view of a coconut drilling device showing my new design;

FIG. 2 is a rear elevational view thereof;

FIG. 3 is a left side view thereof;

FIG. 4 is a right side view thereof;

FIG. 5 is a Top View thereof;

FIG. 6 is a Bottom View thereof; and

FIG. 7 is a Perspective View(from top) thereof; and,

FIG. 8 is a Reference View(from bottom) thereof.
